UNITED STATES PATENT OFFICE.

ALFRED E. STRINGER, OF CHICAGO, ILLINOIS.

SOIL-PIPE DRAINAGE SYSTEM.

Application filed January 14, 1927. Serial No. 161,055.

This invention relates to piping systems, with special reference to soil and vent pipe joints, permitting expansion when solidly embedded in concrete or the like.

5 Heretofore large fire proof buildings have been constructed with steel frames and hollow tile floors, in which case the shell of the building can be completed to the roof before the plumbers come in to make their installation, the mechanic having each floor to support and distribute the weight of the piping. Within the last few years, concrete construction has come to the front and in such a case the plumbers must install 10 the piping before pouring each floor and the mechanic is obliged to run his pipe up in the air above the highest floor that is to be poured, keeping one set of piping suspended in the air above each floor of concrete. 15 This piping all has to be set in place and so suspended that the concrete pourers can then come along and pour their concrete enclosing or embedding the fittings into the concrete, so that provision must be made 20 for the expansion in the pipes caused by waste hot water from bathtubs and the like. Because the heavy upstanding piping must be supported by the embedded fitting, it is an object of this invention to provide a 25 soluble gasket of sufficient hardness and strength to initially support the piping from the end, this gasket being dissolved out during the testing of the piping after the concrete hardens and supports the piping. 30

35 The removal of the gasket leaving space for the expansion of the pipe which would otherwise be apt to crack the fittings. As an alternative, a yielding supporting gasket can be used which will permit expansion 40 while being stiff enough to support the original dead weight of the pipe.

45 Other and further important objects of this invention will be apparent from the disclosures in the specification and the accompanying drawings.

This invention (in a preferred form) is illustrated in the drawings and hereinafter more fully described.

On the drawings:

50 Figure 1 is a section through a multiple branch elbow fitting, showing the expansion joints of this invention as first set up.

Figure 2 is a section similar to Figure 1,

showing the space allowed for lengthwise movement of the risers due to the removal 55 of the soluble gasket.

Figures 3, 4 and 5 disclose three illustrative piping layouts to show the various locations for expansion joints.

As shown on the drawings: 60 A multiple branch fitting 10 is shown in Figures 1 and 2 and intended to be imbedded in the concrete to replace a group of elbows and T's connected by nipples. The bottom outlet 11 is threaded for iron or 65 steel pipe, while the two vertical outlets 12 and 13 are arranged for expansion joints in connection with the straight ends of pipes 14 and 15. The side outlet 16 is arranged for the customary oakum and caulked lead 70 joint used with cast iron pipe. The expansion joints on the outlets 12 and 13 comprise a flat inner seat shoulder 17 intended to receive a soluble or flexible gasket 18 to initially support the weight of the upstanding 75 piping, a suitable soluble gasket material being wood pulp, sawdust or sand moulded with a soluble binder, such as glue. The entire material may be made of a soluble 80 material, if so desired. If a yielding or flexible gasket is desired, a cork or rubber compound may be used. The pipe ends 14 and 15 rest on this gasket and the joint is sealed in the bell mouth shown on the outlets, oakum 19 and caulked lead 20 providing 85 a suitable seal that will allow longitudinal movement of the pipe.

In Figure 3 a very complete installation is shown using the combined fitting 10 embedded in the floor with a threaded pipe 21 90 used as the main soil pipe below the top floor and having expansion joints with the fittings on the lower floors. The usual cast iron vent pipe 22 is used with a threaded revent pipe 23 having expansion joints on 95 the lower ends thereof, a number of waste pipes 24 leading into a lateral 25 and having expansion joints at top and bottom.

Figure 4 shows a system resembling Figure 3, but having a cast iron soil pipe stack 100 26 with the threaded steel revent pipe 23 as before. In this case, expansion joints may be used or for the soil pipe short lengths thereof may provide sufficient flexibility, depending on the anticipated amount of expansion due to the number of hot water 105

waste connections. In this case the soil pipe is not intended to be inclosed in the concrete but the revent pipe will be, so that expansion joints are essential on the revent, because 5 this pipe is frequently also used for a waste pipe and is subject to expansion caused by hot water.

In Figure 5 cast iron soil pipe is used, both for the main stack 26 as in Figure 4 and on 10 the revent as indicated by the numeral 27. The required expansion joints are used on the waste pipes and revent as before, these joints being required wherever expansion is liable to damage fittings embedded in the 15 concrete. Another important point is that these fittings take care of not only the expansion from the change in temperature in the system due to hot water and seasonal variations, but serve as well to avoid breakage due to settling, which occurs in nearly 20 every new building after it has been erected and frequently causes breaks in pipe and fittings rigidly installed and connected in the building.

I am aware that many changes may be made, and numerous details of construction may be varied through a wide range without departing from the principles of this invention, and I therefore do not purpose 30 limiting the patent granted hereon, otherwise than necessitated by the prior art.

I claim as my invention:

1. An expansion joint for pipes comprising a bellmouthed socket, means insertable in the bottom of said socket for temporarily supporting a length of pipe, and permanent sealing means in said socket around said pipe adapted to permit longitudinal movement of said pipe relative to said socket.
2. A multiple branch pipe fitting adapted to be embedded in concrete, expansion joints on said branches, and means within said expansion joints adapted to temporarily

support the weight of the pipe during the erection of a stack of piping.

3. A multiple branch pipe fitting adapted 45 to be embedded in concrete, expansion joints on said branches, and soluble gaskets below the pipe ends in said expansion joints adapted to temporarily support the weight 50 of the pipe during the erection of a stack of piping.

4. An expansion joint for a pipe stack comprising a bell-mouthed socket having an interior shelf aligned with the end of the 55 pipe to be inserted therein, a soluble gasket positioned between the pipe end and the shelf for temporarily supporting the up-standing pipe stack during the pouring of concrete thereabout, and packing around 60 said pipe and spaced from said soluble gasket.

5. A pipe stack adapted to be embeded in concrete comprising branch fittings, expansion joints between adjacent fittings, and 65 means adapted to temporarily support the superimposed portion of the stack while pouring concrete thereabout.

6. A pipe stack adapted to be embedded in concrete comprising branch fittings, expansion joints between adjacent fittings, and means within said expansion joints adapted to temporarily support the superimposed portion of the stack while pouring concrete 70 thereabout.

7. An expansion joint for a pipe stack comprising a socket adapted to receive a pipe end, said socket having an interior support for said pipe end, and a soluble gasket positioned between said pipe end and said 75 support for temporarily sustaining the weight of the superimposed pipe.

In testimony whereof I have hereunto subscribed my name at Chicago, Cook County, Illinois.

ALFRED E. STRINGER.
